(57) **CLAIM**

The ornamental design for a safety strip and mount, as shown and described above.

DESCRIPTION

FIG. 1 is a perspective view of a safety strip;

FIG. 2 is a side elevational view thereof;

FIG. 3 is a front elevational view thereof;

FIG. 4 is a side elevational view thereof;

FIG. 5 is a rear elevational view thereof; and,

FIG. 6 is a left side elevational view thereof, the right side view being a mirror image.

The break in the FIGS. 1, 2, 3, 4, 5 and 6 drawings show indeterminate length. has been inserted into the specification preceding the broken line description.

In the drawings, the broken lines in FIG. 1 show portions of a safety strip that form no part of the claimed design.
